LABRON P. JONES, OF CALHOUN FALLS, SOUTH CAROLINA, ASSIGNOR OF TWO-FIFTHS
TO W. T. STOREY, OF CALHOUN FALLS, SOUTH CAROLINA, AND ONE-FIFTH TO
J. M. NICKLES, OF ABBEVILLE, SOUTH CAROLINA.

SPOON FOR STOP-MOTION MECHANISM.

Application filed July 11, 1928. Serial No. 291,905.

This invention relates to a spoon forming an element of the stop motion mechanism of drawing frames for cotton and wool spinning, but it is to be understood that a spoon, 5 in accordance with this invention may be employed in any connection for which it is found applicable, and the invention has for its object to provide, in a manner as hereinafter set forth, a spoon of the class referred 10 to so constructed and arranged as to render is quickly responsive, on any break in the sliver or when the latter runs out to coact with an element of the stop motion mechanism of the frame or machine to cause the 15 instant stoppage of the latter.

A further object of the invention is to provide, in a manner as hereinafter set forth, 20 a spoon for the purpose referred to including a head having a rearward extension acting as a weighting means to render the spoon when occasion requires quickly responsive to coact with an element of the stop motion mechanism of the machine to provide for the instant stoppage of the latter when the 25 sliver is drawn out or breaks.

A further object of the invention is to provide, in a manner as hereinafter set forth, 30 a spoon for the purpose referred to including a head providing a combined sliver guide and retainer, and further with the head having a rearward extension acting as a weighting means to render the spoon quickly responsive to provide for the instant stoppage of the machine when occasion requires.

A further object of the invention is to provide, in a manner as hereinafter set forth, 35 a weighted spoon so constructed and arranged to act as a sliver guide and retainer and also as an element of the stop motion mechanism of the machine to provide for the instant stoppage of the machine on any break in the sliver, as well as when it shifts off the spoon and further when drawn out.

Further objects of the invention are to provide, in a manner as hereinafter set forth, 45 a spoon for the purpose referred to which is simple in its construction and arrangement, strong, durable, compact, thoroughly efficient in its use, and comparatively inexpensive to manufacture.

With the foregoing and other objects in view the invention consists of the novel construction, combination and arrangement of

parts as hereinafter more specifically described, and illustrated in the accompanying 55 drawings, wherein is shown an embodiment of the invention, but it is to be understood that changes, variations and modifications can be resorted to which fall within the scope of the claims hereunto appended. 60

In the drawings wherein like reference characters denote corresponding parts throughout the several views:—

Figure 1 is a sectional elevation of a drawing frame showing the adaptation therewith 65 of a spoon in accordance with this invention and free of connection with its associated element of the stop motion.

Figure 2 is a fragmentary view, upon an enlarged scale of a drawing frame showing 70 the adaptation therewith of a spoon in accordance with this invention and free of connection with its associated element of the stop motion.

Figure 3 is a perspective view of the spoon. 75
Figure 4 is an elevation looking toward the forward end of the spoon.

Figure 5 is a sectional elevation looking to that side of the spoon opposite to that shown in Figure 3. 80

Referring to the drawings 1 indicates the can from which the sliver is drawn and 2 designates the can which receives the sliver. The drawing frame is indicated generally at 3 and includes the blade 4 of the stop motion 85 therefor. The frame 3 includes a knife-edge bar 5 upon which is pivoted or hung a spoon in accordance with this invention and which is generally indicated at 6. The spoon 6 pivots or vibrates on the knife-edge bar 5. 90

It is not deemed necessary to completely represent and describe the stop motion mechanism, other than the parts 4, 5 and 6, inasmuch as this mechanism is well known to those skilled in the art, and forms no part 95 of this invention other than the spoon 6.

The spoon 6 comprises a shank 7 of arcuate cross section and of appropriate length. At the lower end of the shank 7 a pair of opposed, forwardly directed, spaced protuberances 8 are provided having their top edges 9 inclining upwardly from the inner to the outer ends thereof. The protuberances 8 are adapted to provide for the coupling of the spoon 6 with the blade 4 to cause the stop motion to become active when the sliver 105

breaks or is drawn out. This arrangement and function is well known.

The upper end of the shank 7 is formed with a pair of forwardly directed lugs 11 having the bottom edges 12 thereof inclining downwardly from the inner to the outer ends thereof. The lugs 11 provide for hanging, mounting or pivoting the spoon 6 on the knife edge of bar 5, the latter being positioned above blade 4. The shank 7 provides a counterbalance or weighting means for the head of the spoon to be presently referred to. This arrangement and function is well known.

15 The spoon 6, in accordance with this invention includes a substantially channel shaped head formed of a tapered base part 13 providing a continuation of the upper end of shank 7, but inclines slightly forward with respect to the latter. Formed integral with one side of the base part 13 is a forwardly directed semi-oval shaped side cheek part 14 which inclines inwardly from its lower to its upper end and further inclines outwardly 25 from its junction with the base part 13.

At the other side of the base part 13, there is formed integral therewith a cheek part 15 inclining inwardly from its top to its bottom and formed integral with the base part 13. 30 The cheek part 15 inclines outwardly from its junction with the base part 13. The cheek part is substantially semi-oval and opposes in spaced relation cheek part 14.

The cheek part 15 merges into a downwardly extending, rearwardly inclined combined sliver guide retainer and spoon weighting means formed of a pair of side parts 16, 17 and a top part 18 which couples the parts 16, 17 together. The part 16 is of greater length 40 than part 17. The part 18 has its upper end incline rearwardly from part 16. The upper portion of the forward edge of part 17 is spaced from the edge of cheek part 14 and substantially opposes the same. The part 18 extends between cheek part 14 and cheek part 15.

The parts 16, 17 and 18 of the combined guide, retaining and weighting element are projected downwardly from the part 15 to 50 oppose the upper portion of the shank and which provide a weighting extension for the spoon, whereby the latter will be quickly responsive to couple itself to the blade 4, when the sliver 10 is drawn out or breaks to cause 55 instant stoppage of the machine. The weighting extension is disposed at a rearward inclination from its upper end.

The cheek part 14 projects beyond the part 18 and which enables the operator of the 60 machine to place the thread or sliver in the spoon more easily, and further the thread or sliver when thrown against cheek part 14 will press down. The cheek part 14 also projects forwardly with respect to cheek part 15.

65 The rear end of the combined guide, retain-

ing and weighting element is formed with an outturned, curved or rounded flange 20 which allows the spoon to lay more heavily upon the sliver without cutting, breaking or severing the latter and for the sliver to pass into 70 the spoon without disturbing the fiber, which would not be the case if the rear end of said element had a sharp corner bearing on the sliver during the drawing operation.

The opening 19 formed between part 18 and cheek 14 permits of the readily insertion of the sliver 10. The parts 17 and 18 provide a retainer for the sliver 10. The cheek part 15 in connection with the cheek 14 and base part 13 provides a guide for the sliver 10. 75

The construction of the head will not allow a singling that is oftentimes made on the cards to pass to the drawing frame, as when the singling passes over the spoon the latter will act to stop the drawing frame instantly, thus 85 preventing the frame from turning out the singling and permitting of an end being left to piece a new end of the singling to, or in other words, the construction of the spoon, in accordance with this invention will instantly provide for the stoppage of the drawing without the making of singlings. 90

By weighting the head in the manner as referred to it will cause the spoon to drop back quickly when the drawing passes through it 95 or the sliver breaks, but even though the head be weighted, the spoon cannot fold back to stop off the frame until the sliver or drawing runs out or the sliver breaks, and at which time the spoon will act to instantly stop the 100 machine.

What I claim is:

1. A spoon for the purpose set forth comprising a shank having inherent means for pivotally suspending it, and a head at one end thereof, said head having a weighting means 105 extended rearwardly therefrom to overlap the shank and independent of the latter.

2. A spoon for the purpose set forth comprising a shank having inherent means for pivotally suspending it, and a head at the 110 forward end thereof, said head having projecting from its rear a weighting means overlapping and inclining upwardly from the shank.

3. A spoon for the purpose set forth comprising a shank having means for pivotally suspending the same, a head extending from one end of the shank and including a pair of cheeks, and weighting means for the spoon 115 projecting rearwardly from one of the cheeks and opposing the shank.

4. A spoon for the purpose set forth comprising a shank having means for pivotally suspending the same, a head extending from one end of the shank and including a pair of cheeks, weighting means for the spoon projecting rearwardly from one of the cheeks and opposing the shank, and said weighting means disposed at an outward inclination 125 130

with respect to the shank and having a part opposing and spaced from the edge of the other of the cheeks.

5. In a spoon for the purpose set forth a head including a pair of cheeks, and a weighting means for the head formed integral with and projecting rearwardly at a downward inclination from one of said cheeks.

6. In a spoon for the purpose set forth a head including a pair of cheeks, and a weighting means for the head formed integral with and projecting rearwardly at a downward inclination from one of said cheeks, said weighting means having a part thereof opposing and spaced from the edge of the other of said cheeks.

7. In a spoon for the purpose set forth, a shank, providing a counterbalance support, a head at the upper end of the shank, and weighting means for the spoon extended rearwardly from the head at the upper end thereof and independent of the shank.

8. In a spoon for the purpose set forth, a shank, a head at the upper end of the shank, and weighting means for the spoon extended rearwardly from one side of the head at the upper end thereof at an inclination with respect thereto and opposing the shank.

9. A spoon for the purpose set forth a channel shaped head, and weighting means for the spoon integral with one side of, extending into and projecting rearwardly from the rear end of the head.

10. In a spoon for the purpose set forth a head including a pair of opposed, spaced cheeks, one projecting above and forwardly with respect to the other, and a weighting means for the head integral with and projecting rearwardly at an inclination from the other of said cheeks and having a part thereof opposing and spaced from the first mentioned cheek, and said means having an outturned flange at its rear.

11. A spoon comprising a shank having inherent means for pivotally suspending it, a head at the upper end of the shank, and a rearwardly extending weighting means integral with and projecting from the head, the said weighting means at its rear end having an outturned flange, said head including a pair of cheek parts, said weighting means being carried by one of said cheek parts and including a pair of coupled side parts opposing and spaced from each other and with one of said side parts having its edge spaced from the edge of the other cheek part.

12. A spoon for the purpose referred to

comprising a shank having inherent means for pivotally suspending it, a head integral with and extending forwardly from the upper end of the shank and including a pair of opposed cheeks, and a combined guide, retaining and weighting means integral with one of said cheeks, said means extending towards and spaced from the other of said cheeks and projecting rearwardly from both cheeks.

13. A spoon for the purpose referred to comprising a shank having inherent means for pivotally suspending it, a head integral with and extending forwardly from the upper end of the shank and including a pair of opposed cheeks, and a combined guide, retaining and weighting means integral with one of said cheeks, said means extending towards and spaced from the other of said cheeks and projecting rearwardly from both cheeks, said means having its rear end formed with an outturned flange.

14. A spoon for the purpose referred to comprising a shank having inherent means for pivotally suspending it, a head integral with and extending forwardly from the upper end of the shank and including a pair of opposed cheeks, and a combined guide, retaining and weighting means integral with one of said cheeks, said means extending towards and spaced from the other of said cheeks and projecting rearwardly from both cheeks, said means having a portion opposing said shank.

15. A spoon for the purpose set forth comprising a combined support and counterbalance element, a head projecting forwardly from the upper end of said element, and a weighting means integral with the head, extending rearwardly therefrom and disposed at an angle with respect to and over said element.

16. A spoon for the purpose set forth comprising a combined support and counterbalance element, a head projecting forwardly from the upper end of said element, and a weighting means integral with the head, extending rearwardly therefrom and disposed at an angle with respect to said element, said head being of channel shape and having the rear end of its bottom integral with the upper end of said element, said means integral with one side of and projecting into said head to provide a sliver retainer.

In testimony whereof I affix my signature hereto.

LABRON P. JONES.
